YARN TENSIONING DEVICE

Edward J. Heizer, West Caldwell, N. J., assignor
to Specialties Development Corporation, Belle-
ville, N. J., a corporation of New Jersey

Application August 22, 1947, Serial No. 770,021

28 Claims. (Cl. 242—45)

1

The present invention relates to an improved yarn tensioning device particularly adapted for use in conjunction with machines for winding yarn on cops, bobbins and the like, or for performing other operations involving the use of yarn.

An object of the present invention is to provide a yarn tensioning device through which the yarn is supplied at a substantially uniform tension.

Another object is to provide a tensioning device adapted to supply the yarn with such uniform output tension even if the input tension of the yarn varies over a wide range.

Another object is to provide a tensioning device which is readily adjustable to tension the yarn at predetermined desired values.

Another object is to provide a readily adjustable tensioning device having indicating means for duplicating desired settings.

Another object is to provide a tensioning device which is readily adjustable to receive yarns of different diameters varying over a relatively wide range.

Another object is to provide a tensioning device which will not damage the yarn.

A further object is to provide a yarn tensioning device which is simple in design, accurate and rapid in operation, and can be manufactured and assembled economically.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description, and is shown in the accompanying drawings, forming a part of the specification, wherein:

Figure 1 is an elevational view of a yarn tensioning device illustrating the present invention, with portions thereof broken away for clearness.

Figure 2 is a sectional view taken along the line 2—2 on Figure 1.

Figure 3 is a sectional view taken along the line 3—3 on Figure 2.

Figure 4 is a sectional view taken along the line 4—4 on Figure 2.

Figure 5 is a fragmentary stepped sectional view of a portion of the device shown in Figure 2, illustrating the operation of the device.

Figure 6 is a perspective view illustrating a detail of the device.

2

Referring to the drawings, there is shown a yarn tensioning device which generally comprises a pair of members such as discs 10 and 11 for receiving yarn therebetween and slightly pinching the yarn to apply the desired tension thereto, and a control arm 12 for effecting separation of the discs to vary the tension applied. This action is accomplished by the construction about to be described.

More specifically, the tensioning device comprises a circular plate or base 15 having a central aperture 16 and a radially extending groove or slot 17 on one side thereof (Figure 4), a stem 19 threaded at the ends thereof having one of its ends extending through the aperture 16 and having a nut 20 or the like applied thereto adjacent the base, and a substantially cylindrical cam member 21 having a nut portion 22 at one end which extends into the groove 17 and having a threaded central aperture 24 into which the stem 19 is threaded, whereby the nut 20 and the cam member 21 cooperate to mount the stem on base 15.

The base 15 has a yarn guide 18 mounted thereon for leading the incoming yarn to the discs 10 and 11, and has a stop 23 mounted thereon adapted to be engaged by the control arm 12.

The cam member 21 (Figure 6) has a cylindrical section 25 adjacent the nut portion 22, which extends through a central aperture 26 of a circular casing or housing 27 rotatably mounted on the base 15 and retained thereon by an enlarged cylindrical section 29 of the cam member. Set screw means 28 on the base serve to secure the housing 27 against relative rotative movement with respect thereto. The end of the section 29 is formed with a pair of 180° cam surfaces 30, the function of which will become apparent hereinafter.

A cup-like retainer 31, having a central aperture 32 for receiving the stem 19 and having a circular recess 34 for receiving the cylindrical section 29, is rotatably mounted with respect to the stem and the cam member 21. The retainer 31 has a pair of apertures 35 extending therethrough which are parallel to and diametrically opposite the aperture 32. Each aperture 35 has a pair of ball bearing members 36 therein, one of which is in contact with one of the cam surfaces 30 and the other of which engages a thrust ring 37 having a central aperture 39 through which the stem 19 extends to mount the ring thereon for endwise and rotative movement.

The arm 12 has one end thereof secured to the retainer 31 and extends tangentially therefrom

Patented May 29, 1951

and is adapted to impart rotative movement to the retainer in response to the output tension of the yarn extending over yarn guide means 40 at the free end of the arm. Such rotative movement of the retainer with respect to the cam member effects endwise movement of the thrust ring 31 as will be described hereinafter. This rotative movement is resisted by a flat spiral spring 41 having one of its ends anchored in a slot 42 in the retainer and having its other end anchored in a slot 44 in the housing 27 (Figure 1). A cover member 45 encloses the spring 41 in the housing 27. Relative positioning of the housing 27 on the base 15 determines the tension of the spring 41.

The discs 10 and 11 are operatively associated with the foregoing elements and are mounted for lateral movement on the stem 19 as about to be described. Each disc has a cylindrical hub 46 telescoped over a cylindrical sleeve 47 through which the stem extends, and the hubs have a radially inwardly facing flange 49. The sleeve 47 has an enlarged bore portion 50 at one end for housing a helical spring 51 one end of which abuts a shoulder 52 within the sleeve and the other end of which engages the flange 49 of the disc 10. The other end of the sleeve 47 engages the flange 49 of the disc 11, whereby the spring 51 acts to urge the discs 10 and 11 relatively apart.

The disc 11 is retained against outward movement toward the end of the stem 19 by a lock nut assembly 53 threaded to the stem, and a felt washer 54 is positioned between the flange 49 of the disc 11 and the lock nut assembly to cushion shocks and to dampen vibrations. Since the lock nut assembly acts as a stop for the disc 11, the spring 51, in tending to separate the discs 10 and 11, urges the flange 49 of the disc 10 against the thrust ring 31. The lock nut assembly may be adjusted to vary the initial space between the discs to thereby enable the discs to accommodate yarns of various diameters.

The device in accordance with the present invention further is provided with indicating means to enable settings at desired tensions to be readily duplicated. To accomplish this, the rim of the housing 27 has indicia thereon for indicating the fraction of one turn the housing has been rotated with respect to the base to load the spring 41 when the indicia registers with an index mark 55 on an indicator member 56 slidably disposed in the groove 17 (Figure 1). The member 56 has indicia thereon adapted to indicate the number of full turns the housing has been rotated, the rim of the housing serving as an index mark for this indicia. In order to slide the member 56 radially outwardly to expose the indicia thereon, the member 56 has a projection or follower 57 on its inner end adapted to ride in a spiral groove 59 formed in the housing (Figure 4). By using dead ends on the spiral groove 59 and limiting the number of convolutions, the total number of turns are limited to prevent over stressing of the spring 41 as well as preventing counter rotation of the spring below its normal relaxed position.

In operation, with the parts of the device assembled as shown, the yarn to be tensioned by the device is threaded through the guide 18, is passed between the discs 10 and 11, and is passed through or over the guide means 40.

The device is then adjusted to load the spring 41 to a desired value, so that the retainer 31 is rotated in a direction to cause the cam surfaces 30 to urge the ball bearing members 36 outwardly and thrust the ring 31 in a direction to overcome

the disc separating spring 51 and hold the discs 10 and 11 together to provide a predetermined pinching effect. This adjustment is accomplished by unfastening the set screw means 28, rotating the housing 27 to the desired spring loading position, and fastening the set screw means.

The lock nut assembly is then adjusted to bring the discs 10 and 11 in the desired yarn pinching position and preferably is so adjusted that the control arm 12 is positioned just above its stop 23.

As yarn is fed through the device for example in a winding or spooling operation, the yarn is pinched by the discs 10 and 11 to apply a uniform output tension to the yarn supplied, regardless of the input tension, which however may not exceed the desired output tension. Should the normal input tension increase, the output tension of yarn supplied by a conventional tension device would increase correspondingly. This, however, is prevented in the manner about to be described.

Upon increase in input tension, the tension of the yarn being supplied tends to increase and raises the control arm 12 in opposition to the spring 41 in proportion to the decreased pinch required to maintain a uniform output tension. The arm rotates the retainer 31 relatively to the cam member 21, whereby the ball bearing members 36 ride downwardly along the cam surfaces 30 and move away from the thrust ring 31, thereby permitting the spring 51 to effect moving apart of the discs 10 and 11 (Figure 5) and lessening the pinch on the yarn in an amount proportionate to the increase in input tension. When the input tension becomes normal again, tension of the yarn being supplied tends to decrease, and the arm 12 is lowered by the action of the spring 41 and the ball bearing members 36 ride upwardly along the cam surfaces 30 and engage the ring 31 to thrust it against the flange of the disc 10 to effect closing of the discs. In this manner, the device supplies yarn having a substantially uniform and constant output tension.

From the foregoing description, it will be seen that the present invention provides an improved tensioning device which supplies the yarn with a substantially uniform and constant output tension regardless of changes in input tensions tending to vary the output tension of the yarn being supplied. The device is readily adjustable to predetermine the tension at which the yarn is to be supplied and is readily adapted for yarns of various diameters. The device is rugged in construction and can withstand such rough usage to which it may be subjected.

The elongated arm 12, the cam surfaces 30, the retainer 31, the ball bearing members 36 and the thrust ring 31, as described herein, provide a high mechanical advantage between the end of the arm 12 and the disc 10 movable with the thrust ring, whereby a substantial movement of the end of the arm 12 results in a very small movement of the disc 10. The effective length of the arm 12 and the pitch of the cam surfaces 30 may be such as to give a ratio greater than twenty to one and preferably greater than sixty to one. Such high mechanical advantage enables the device to compensate for variations in input tension while maintaining the output tension substantially constant.

Also, by utilizing ball bearing members 36 cooperating with the cam surfaces 30 and the thrust ring 31 to control the relative movement of the discs 10 and 11, friction losses in the device are greatly minimized to render it very

sensitive to changes in tension. The sensitivity and responsiveness of the device is further improved by use of the spring 41 which has relatively low inertia.

The term "yarn" as used herein is intended to include strands, filaments, wires, threads, or the like, formed of vegetable, animal or mineral matter.

As various changes may be made in the form, construction and arrangement of the parts herein, without departing from the spirit and scope of the invention and without sacrificing any of its advantages, it is to be understood that all matter herein is to be interpreted as illustrative and not in any limiting sense.

It is also to be understood that the following claims are intended to cover all the generic and specific features of the invention herein described, and all statements of the scope of the invention which, as a matter of language, might be said to fall therebetween.

I claim:

1. A device for tensioning yarn comprising a pair of members for receiving the yarn therebetween, resilient means for urging said members apart, means acting in opposition to said resilient means for moving said members toward each other, and means for operating said last mentioned means whereby tensioning of the yarn is controlled by said members.

2. A device for tensioning yarn comprising a pair of members for receiving the yarn therebetween, resilient means for urging said members apart, cam means for moving said members relatively toward each other in opposition to said resilient means, and means for operating said cam means whereby tensioning of the yarn is controlled by said members.

3. A device for tensioning yarn comprising a pair of members for receiving the yarn therebetween, resilient means for urging said members apart, cam means for moving said members relatively toward each other in opposition to said resilient means, spring means for actuating said cam means, and means for operating said spring means whereby tensioning of the yarn is controlled by said members.

4. A device for tensioning yarn comprising a stem, a pair of friction discs for receiving the yarn therebetween mounted on said stem for axial movement thereon, a stop on said stem for determining the extent of axial movement of said discs, resilient means for urging said discs apart, means acting in opposition to said resilient means for moving said discs relatively toward each other, and means for operating said last mentioned means whereby tensioning of the yarn is controlled by said discs.

5. A device for tensioning yarn comprising a pair of relatively movable members for receiving the yarn therebetween, means for urging said members apart, means acting to urge said members toward each other, and means controlled by the tension in the yarn having a high mechanical advantage for operating said last mentioned means whereby tensioning of the yarn is controlled by said members.

6. A device for tensioning yarn comprising a pair of relatively movable members for receiving the yarn therebetween, means for urging said members apart, cam means for moving said members relatively toward each other, and means controlled by the tension in the yarn for operating said cam means whereby tensioning of the yarn is controlled by said members.

7. A device for tensioning yarn comprising a pair of relatively movable members for receiving the yarn therebetween, means for urging said members apart, cam means for moving said members relatively toward each other, and means for operating said cam means including an elongated arm responsive to the tension in the yarn, whereby tensioning of the yarn is controlled by said members.

10. 8. A device for tensioning yarn comprising a pair of relatively movable members for receiving the yarn therebetween, spring operated means acting to move said members relatively toward each other, means responsive to the tension in

15. the yarn for operating said spring operated means to render the same at least partially ineffective, and means for adjusting said spring operated means.

9. A device for tensioning yarn comprising a 20 pair of relatively movable members for receiving the yarn therebetween, spring operated means acting to move said members relatively toward each other, means responsive to the tension in the yarn for operating said spring operated 25 means to render the same at least partially ineffective, means for adjusting said spring operated means, and means for indicating the adjustment of said spring operated means.

10. A device for tensioning yarn comprising a 30 pair of members mounted for relative lateral movement adapted to receive the yarn therebetween, means for urging said members apart, means for adjusting the extent of movement of said members, means for moving said members 35 relatively toward each other, and means responsive to the tension in the yarn for operating said last mentioned means whereby tensioning of the yarn is controlled by said members.

11. A device for tensioning yarn comprising a 40 stem, a pair of relatively movable friction discs for receiving the yarn therebetween mounted on said stem, a cam, means relatively movable with respect to said cam and actuated thereby to move said discs relatively toward each other, 45 a member mounted for rotation on said stem and associated with said last mentioned means to cause the same to be actuated by said cam, a spring urging said member into a position to effect movement of said discs toward each other, 50 and an arm on said member responsive to the yarn for operating said member in opposition to said spring to decrease the effectiveness of said cam actuated means to effect relative movement of said discs toward each other.

55. 12. A device for tensioning yarn comprising a base, a stem having one end secured to said base, a cam fixed on said stem adjacent said base, a housing member rotatably mounted on said stem, an arm secured to said housing member, 60 a spring coiled about said housing member and having one end attached thereto, cam follower means associated with said cam and said housing means, a pair of friction discs for receiving the yarn therebetween mounted on said stem for axial movement thereon, one of said discs being engaged by said cam follower means, and a stop on said stem for engaging the other of said discs to determine the extent of axial movement thereof.

70. 13. A device for tensioning yarn comprising a base, a stem having one end secured to said base, a cam fixed on said stem adjacent said base, a housing member rotatably mounted on said stem, an arm secured to said housing member, a spring 75 coiled about said housing member and having

one end attached thereto, a casing member rotatably mounted about said stem having the other end of said spring attached thereto to vary the tension of the spring, cam follower means associated with said cam and said housing means, a pair of friction discs for receiving the yarn therebetween mounted on said stem for axial movement thereon, one of said discs being engaged by said cam follower means, and a stop on said stem for engaging the other of said discs to determine the extent of axial movement thereof.

14. A device for tensioning yarn comprising a base, a stem having one end secured to said base, a cam fixed on said stem adjacent said base, a housing member rotatably mounted on said stem, an arm secured to said housing member, a spring coiled about said housing member and having one end attached thereto, a casing member rotatably mounted about said stem having the other end of said spring attached thereto to vary the tension of the spring, cam follower means associated with said cam and said housing means, a pair of friction discs for receiving the yarn therebetween mounted on said stem for axial movement thereon, one of said discs being engaged by said cam follower means, a stop on said stem for engaging the other of said discs to determine the extent of axial movement thereof, and indexing means associated with said base and casing member for indicating the adjustment of said spring.

15. A device for tensioning yarn comprising a base, a stem having one end secured to said base, a cam fixed on said stem adjacent said base, a housing member rotatably mounted on said stem, an arm secured to said housing member, a spring coiled about said housing member and having one end attached thereto, a casing member rotatably mounted about said stem having the other end of said spring attached thereto to vary the tension of the spring, cam follower means associated with said cam and said housing means, a pair of friction discs for receiving the yarn therebetween mounted on said stem for axial movement thereon, one of said discs being engaged by said cam follower means, an adjustable stop on said stem for engaging the other of said discs to determine the extent of axial movement thereof, resilient means for urging said discs apart, and indexing means associated with said base and casing member for indicating the adjustment of said spring.

16. In a yarn tensioning device including yarn tensioning means and a spring for operating the tensioning means, the combination of a base member having a radially extending groove therein, a member rotatably mounted on said base member for varying the tension of the spring and having a spiral groove adjacent said radial groove, a member slidably mounted in said radial groove having a portion extending into said spiral groove whereby upon rotation of said rotatable member said slidible member is moved radially, and indexing means on said slidible member for indicating the relative rotation between said rotatable member and said base member.

17. In a yarn tensioning device including yarn tensioning means and a spring for operating the tensioning means, the combination of a base member having a radially extending groove therein, a member rotatably mounted on said base member for varying the tension of the spring and having a spiral groove adjacent said radial groove, a member slidably mounted in said

radial groove having a portion extending into said spiral groove whereby upon rotation of said rotatable member said slidible member is moved radially, indexing means on said slidible member for indicating the relative rotation between said rotatable member and said base member, and means for securing said rotatable member against rotation with respect to said base member.

18. A device for tensioning yarn comprising a pair of relatively movable members for receiving yarn therebetween, means for urging said members apart, means acting in opposition to said first means for moving said members relatively toward each other, and means for operating said last mentioned means responsive to the tension in the yarn.

19. A device for tensioning yarn comprising a pair of relatively movable members for receiving the yarn therebetween, resilient means for urging said members apart, and means acting in opposition to said resilient means for urging said members toward each other including means having a high mechanical advantage.

20. A device for tensioning yarn comprising a pair of relatively movable members for receiving yarn therebetween, means for urging said members apart, means for moving said members relatively towards each other, and means including an elongated arm controlled by the tension in the yarn for rendering said last mentioned means at least partially ineffective to facilitate movement of said members to control the tensioning of the yarn.

21. A device for tensioning yarn comprising a stem, yarn tensioning means including a pair of relatively movable members mounted on said stem, a cam, means relatively movable with respect to said cam and actuated thereby to move said members relatively toward each other, a member mounted for rotation on said stem constructed to arrange said last mentioned means for actuation by said cam, a spring for urging said rotatable member into a position to cause said last mentioned means to effect movement of said first members toward each other, and an arm on said rotatable member responsive to the yarn tension for operating said rotatable member in opposition to said spring to decrease the effectiveness of said cam actuated means to effect relative movement of said first members toward each other.

22. A device for tensioning yarn comprising a base, a stem having one end secured to said base, a cam fixed on said stem adjacent said base, a housing member rotatably mounted on said stem, a spring having one end attached to said base and having its other end attached to said housing member, an arm responsive to the yarn tension secured to said housing member for moving the same in opposition to said spring, cam follower means associated with said cam and said housing means, and yarn tensioning means including a pair of members on said stem, one of said pair of members being mounted for axial movement on said stem and being engaged by said cam follower means and movable thereby.

23. A device for tensioning yarn comprising a base, a stem having one end secured to said base, a cam fixed on said stem adjacent said base, a housing member rotatably mounted on said stem, a spring coiled about said housing member and having one end attached thereto, a casing member rotatably mounted about said stem having the other end of said spring attached thereto to

vary the tension of the spring, an arm responsive to the yarn tension secured to said housing member for moving the same in opposition to said spring, cam follower means associated with said cam and said housing means, and yarn tensioning means including a pair of members on said stem, one of said pair of members being axially movable on said stem and being engaged by said cam follower means and movable thereby.

24. A device for tensioning yarn comprising a stem, a fixed cam on said stem, a housing member rotatably mounted on said stem provided with axially extending aperture means having one end adjacent said cam, a member axially movable on said stem and adjacent the other end of said aperture means, cam follower means movably mounted in said aperture means and operatively connecting said cam and said axially movable member, a spring for rotatably urging said housing member in one direction, an arm responsive to the yarn tension on said housing member for moving the same in opposition to said spring, and yarn tensioning means including a pair of members on said stem one of which is axially movable thereon and is engaged by said axially movable member to effect movement thereof.

25. A device for tensioning yarn comprising a stem, a fixed cam on said stem having a pair of cam surfaces, a housing member rotatably mounted on said stem provided with a pair of axially extending apertures, each having one end adjacent one of said cam surfaces, a member axially movable on said stem and adjacent the other end of said apertures, spherical means movably mounted in said apertures and operatively connecting said cam surfaces and said axially movable member, a spring for rotatably urging said housing member in one direction, an arm responsive to the yarn tension on said housing member for moving the same in opposition to said spring, and yarn tensioning means including a pair of members on said stem one of which is axially movable thereon and is engaged by said axially movable member to effect movement thereof.

26. A device for tensioning yarn comprising a stem, a fixed cam on said stem, a housing member rotatably mounted on said stem provided with axially extending aperture means having one end adjacent said cam, a member axially movable on said stem and adjacent the other end of said aperture means, cam follower means movably mounted in said aperture means and operatively connecting said cam and said axially movable member, a spring for rotatably urging said housing member in one direction, an arm responsive to the yarn tension on said housing member for moving the same in opposition to said spring, yarn tensioning means including a

pair of members on said stem one of which is axially movable thereon and is engaged by said axially movable member to effect movement thereof, and means on said stem for adjusting the axial position of the other of said pair of members.

27. A device for tensioning yarn comprising a pair of relatively movable members for receiving the yarn therebetween, a fixed cam, follower means engaging said fixed cam and being movable with respect thereto and including an element engaging one of said members, a spring normally acting to urge said follower means in a direction whereby said element acts to move said member engaged thereby toward said other member, an arm connected to said follower means responsive to the tension in the yarn for moving said follower means in opposition to said spring to render said element at least partially ineffective, and means for adjusting the force exerted on said follower means by said spring.

28. A device for tensioning yarn comprising a pair of relatively movable members for receiving the yarn therebetween, a fixed cam, follower means engaging said fixed cam and being mounted for rotation with respect thereto and including an element engaging one of said members, a spring normally acting to rotate said follower means in a direction whereby said fixed cam permits said follower means to move in an axial direction to cause said element to move said member engaged thereby toward said other member, an arm connected to said follower means responsive to the tension in the yarn for rotating said follower means in opposition to said spring to render said element at least partially ineffective, and means for adjusting the force exerted by said spring to rotate said follower means.
